SULFATED CHLOROALKANOL DETERGENTS

John C. Cowan, Peoria, Ill., and James Knerr Weil, North Wales, and Alexander James Stirton, Philadelphia, Pa., assignors to the United States of America as represented by the Secretary of Agriculture

No Drawing. Original application Sept. 14, 1954, Ser. No. 456,085. Divided and this application Feb. 1, 1957, Ser. No. 640,999

3 Claims. (Cl. 252—161)

(Granted under Title 35, U.S. Code (1952), sec. 266)

A non-exclusive, irrevocable, royalty-free license in the invention herein described, throughout the world, for all purposes of the United States Government, with the power to grant sublicenses for such purposes, is hereby granted to the Government of the United States of America.

This application is a division of application bearing Serial No. 456,085, filed September 14, 1954, now abandoned.

This invention relates to processes for producing new and improved detergents and surface-active agents comprising alkali metal salts of sulfated polychloroalkanols.

Sulfated alcohols are valuable detergents and are particularly useful where good foaming properties are required despite the use of hard water. When the higher straight-chain saturated alcohols are sulfated it is observed that detergency and foam-forming power increases as the alkyl group of the alcohol increases from 12 to 18 carbon atoms. However, at the same time, solubility in water decreases in the same order; hence the more effective compounds are of such low solubility that they cannot be used alone but must be used along with more soluble, but less effective, detergents.

It is known that olefinic double bonds increase the solubility of long-chain compounds. However, such double bonds are chemically reactive and, unless special precautions are taken, will react with the sulfating agent, thus yielding a product having poor detergent properties.

It is also known that chlorine atoms attached to the alkyl group increase solubility, and it has been proposed to prepare detergents from unsaturated alcohols by chlorinating and then sulfating or by simultaneously hydrochlorinating and sulfating such alcohols. When chlorinated alcohols were sulfated by prior art processes, however, some or all of the chlorine was replaced by sulfate groups, thus yielding inferior detergents. When hydrochlorination was used only one atom of chlorine was introduced at each double bond and the beneficial effect was correspondingly small. Use of more highly unsaturated alcohols permitted the introduction of more chlorine but increased the cost of the alcohol correspondingly.

It is an object of this invention to provide sulfated polychlorinated, long-chain alkanols that are readily soluble in water and also are highly efficient detergents and surface active agents. Another object is to provide economical processes whereby high titer animal fats, such as tallow and grease, can be converted and high detergency. Another object is to provide economical processes whereby highly soluble detergents useful for solubilizing and up-grading other detergents having only slight solubility may be prepared. Still another object is to provide processes for sulfating chloroalkanols whereby the chlorine is not replaced by sulfate groups. Other objects will appear hereinafter.

According to the invention, fatty alcohol compositions containing at least about 10% of monounsaturated alcohols and not more than about one half as much poly-

2

unsaturated as monounsaturated alcohols are chlorinated until substantially all double bonds have been saturated with chlorine; then the alcohols are sulfated at a temperature below that at which the sulfating agent reacts with the chlorine in the alcohols; and finally, the resulting sulfated alkanols are neutralized with an alkali to yield the detergent compounds.

By the expression "fatty alcohol composition" we mean a composition consisting essentially of one or more long, straight-chain aliphatic primary alcohols having 10 to 24 carbon atoms, such as, for instance, dodecyl, tetradecyl, hexadecyl, octadecyl, oleyl, linoleyl, elaidyl and similar alcohols and mixtures thereof, and also the mixed fatty alcohols obtained by the reduction of coconut, palm, cottonseed or partially hydrogenated fish oils, tallow, grease or lard, or the methyl esters derived from such fats and oils. By "alkali" we mean the oxide, hydroxide or carbonate of an alkali metal.

When the product is to be used directly, that is, without first being blended with other detergents, we may use as starting material a fatty alcohol composition containing as little as about 10% of monounsaturated alcohols; where it is to be used for blending with other detergents for the purpose of up-grading or solubilizing them, we prefer to start with fatty alcohols containing at least 40 to 50% of monounsaturated alcohols. In either case a minor amount of polyunsaturated alcohols, up to about one half the amount of monounsaturated alcohols may be tolerated and, in fact, may be desirable, especially when the total unsaturation is relatively low. The preferred raw material for our process is the mixed alcohols obtained from tallow, for instance by sodium reduction, referred to hereinafter as tallow alcohols. Tallow not only has a suitable fatty acid composition but is available in ample quantities at low cost. The commercial inedible greases are likewise especially suitable.

The chlorination of the unsaturated fatty alcohols is carried out as described in the copending application of John C. Cowan and Howard M. Teeter, filed October 11, 1954, Serial No. 461,691, now abandoned. The alcohol is dissolved in a suitable inert solvent, such as a chlorinated hydrocarbon, and chlorine is passed into the solution while the temperature is maintained below that at which substitution occurs. We prefer a temperature in the range —30 to 10° C. and, better yet, below 0° C. The chlorine is rapidly and completely absorbed until the alcohol is substantially saturated, at which point absorption of chlorine and evolution of heat substantially cease. The chlorinated fatty alcohol is then recovered in practically quantitative yield by evaporation of the solvent.

The chloroalcohols may be sulfated by use of any suitable sulfating agent, such as chlorosulfonic acid, sulfuric acid, oleum or sulfur trioxide. The preferred reagent, because of its efficiency and convenience, is chlorosulfonic acid. In order to avoid replacement of chlorine in the alcohol with sulfate groups it is essential to conduct the sulfation at a temperature below that at which replacement occurs. The temperature should not exceed about 50° C. during the sulfation and preferably should be kept below about 30° C. and may be as low as 0°, at least until most of the material has reacted. Since the reaction is strongly exothermic, it is essential that the reagents be mixed slowly with efficient stirring and cooling. This is facilitated by the use of a suitable inert solvent which may conveniently be the same as was used for the chlorination step. In fact, it is not necessary to recover the chloroalcohol from the solution obtained in the chlorination step. Instead, after completion of the chlorination the excess chlorine may be removed by aeration, boiling, or otherwise, after which the solution

of chloroalcohol is cooled and sulfated as described above. This is in general the preferred procedure.

After completion of the sulfation step the reaction mixture is neutralized with an alkali metal hydroxide or carbonate and the resulting salt of the chloroalkyl sulfate is recovered by any suitable means.

Tallow, our preferred raw material, is composed of approximately 1-6% myristic acid, 21-35% palmitic acid, 14-30% stearic acid, 36-50% oleic acid and 1-5% polyunsaturated acids. The tallow alcohols obtained by the sodium reduction of tallow contain about the same percentages of the corresponding alcohols.

Several experiments were made to illustrate the solubility of the sodium chloroalkyl sulfates and their effect in the solubilization of similar detergents made from saturated fatty alcohols. The solubility of each of 4 compositions was determined by dissolving 0.250 g. of the composition in 100 ml. of hot water, letting the solution stand at 25° C. for several days, and then recovering and weighing the precipitate. The compositions were made up from pure compounds to simulate various products as follows:

- A. Sulfated tallow alcohols
- B. Sulfated hydrogenated tallow alcohols
- C. Chlorinated sulfated tallow alcohols
- D. Same as (C) but with chlorinated components omitted

Table I shows the composition of each of the 4 mixtures and the solubility.

TABLE I
Comparative solubility of sulfated tallow alcohols

Component, grams	A from oleyl alcohol	A from elaidyl alcohol	B	C from oleyl alcohol	C from elaidyl alcohol	D
Na tetradearyl sulfate	0.015	0.015	.015	.015	.015	.015
Na hexadecyl sulfate	0.070	0.070	.070	.065	.065	.065
Na octadecyl sulfate	0.040	0.040	.165	.035	.035	.035
Na oleyl sulfate	0.125	0.125	-----	-----	-----	-----
Na elaidyl sulfate						
Na 9,10-dichlorooctadecyl sulfate (from oleyl alcohol)				.135	-----	-----
Na 9,10-dichlorooctadecyl sulfate (from elaidyl alcohol)					.135	-----
Total weight of compo- nents in mixture, grams	0.250	0.250	.250	.250	.250	.115
Insoluble at 25° C., grams	0.068	0.052	.226	.052	.044	.101
Solubility of mixture at 25° C., grams/100 ml.	0.182	0.198	.024	.198	.206	.014

The results show that like mixtures containing either sodium oleyl sulfate, sodium elaidyl sulfate or sodium 9,10-dichlorooctadecyl sulfates have about the same solubility at 25° C., namely 0.2%, while the solubility of the sulfated hydrogenated tallow alcohols (B) is only about 0.02%. Solubilization of the difficultly soluble sodium hexadecyl sulfate and sodium octadecyl sulfate occurs for mixtures A and C since the amount insoluble from mixture D exceeds the amount insoluble from mixtures A and C. Sodium 9,10-dichlorooctadecyl sulfates of mixture C, are therefore soluble alone and also solubilize sodium hexadecyl sulfate and sodium octadecyl sulfate, and are just as effective as sodium oleyl sulfate and sodium elaidyl sulfate in this respect.

The alkali metal salts of the chlorinated fatty alcohol sulfates (polychloroalkyl sulfates) of the invention are likewise effective solubilizing agents for other difficultly soluble anionic detergents. Such an agent is useful where the solubility is below about 0.2%. In such cases, as little as 10% of the polychloroalkyl sulfate detergents

incorporated into the composition significantly improves its solubility and detergent properties. Anionic detergents in which these solubilizing agents are especially effective include the soaps of the higher saturated fatty acids, that is, those containing 14 or more carbon atoms, sodium salts of α -sulfonated palmitic and stearic acids and alkylarylenesulfonate salts having a solubility at 25° C. of less than about 0.2%.

The preparation of sodium 9,10-dichlorooctadecyl sulfates, of chlorinated sulfated tallow alcohols, and the measurement of detergent and surface active properties are illustrated in the following examples.

EXAMPLE I

Chlorination of octadecanols.—Purified oleyl alcohol, I No. 92.5, estimated purity 97%, was prepared from commercial oleyl alcohol by fractional vacuum distillation and crystallization from acetone at 0° C., -45° C., and -10° C., following the method of Swern, Knight and Findley (Swern, D., Knight, H. B., and Findley, T. W., Oil & Soap 21, 133-9 (1944)). A slow stream of chlorine gas was introduced into a stirred solution of 100 g. of purified oleyl alcohol in 300 ml. of dichloromethane, cooled in a dry ice-carbon tetrachloride bath maintained at -45° C. Chlorine was added at such a rate that the reaction temperature remained in the range -13° C. to -23° C. throughout 4½ hours. Completion of the reaction was indicated by the development of a yellow-green color in the solution and a fall in reaction temperature as a result of no further heat of reaction. Solvent and excess chlorine were removed at reduced pressure. The reaction mixture was finally heated on the steam bath to remove the last trace of solvent and to give a 9,10-dichlorooctadecanol as a colorless oil, yield 97%, M.P. 12° C., n_D^{20} 1.4760, d_4^{20} 0.9898, molecular refractivity 96.71 (theoretical value 96.58), I No. 0.3, 19.63% Cl (calculated for $C_{18}H_{36}Cl_2O$, 20.90% Cl; calculated with correction for saturated impurities in the oleyl alcohol, 20.46% Cl).

Elaidyl alcohol, I No. 94.7, M.P. 36.1-37.0° C., was prepared as described by Weil, Stirton and Bistline (Weil, J. K., Stirton, A. J., and Bistline, R. G., Jr., J. Am. Oil Chemists' Soc., 31, 000 (1954)), and chlorinated in a similar manner to give 94% yield of a 9,10-dichlorooctadecanol as a white solid, M.P. 31° C., n_D^{20} 1.4757, d_4^{20} 0.9946, molecular refractivity 96.19, I No. 0.3, 20.59% Cl.

Sulfation of 9,10-dichlorooctadecyl alcohol.—Chlorosulfonic acid, 17 g. (0.15 mole), was added dropwise to a cold, stirred, solution of 40 g. (0.12 mole) of 9,10-dichlorooctadecanol (from oleyl alcohol, above) in 100 ml. of chloroform, at 6° to 10° C. The reaction mixture was heated to 37° C., maintained at 37° C. for ½ hour, cooled, and neutralized with NaOH, n-butanol, 100 ml., was added and water and chloroform were removed together by distillation. In organic salts were filtered off from the dry, boiling, butanol solution. The butanol solution was cooled to -25° C., and filtered to give a 65% yield of a sodium 9,10-dichlorooctadecyl sulfate, a light cream colored solid, purified by treatment with carbon and recrystallization from butanol at -25° C. to give a 39% yield of a sodium 9,10-dichlorooctadecyl sulfate, a white solid, I No. 0.1, containing 5.01% Na, 7.07% S, and 15.39% Cl (calculated for $C_{18}H_{35}Cl_2NaO_4S$, 5.21% Na, 7.26% S, 16.06% Cl; 15.72% Cl when corrected for saturated impurities in the oleyl alcohol).

Elaidyl alcohol, chlorinated and sulfated as described above gave 84% yield of a light cream colored solid and 67% yield of a purified sodium 9,10-dichlorooctadecyl sulfate, a white solid, I No. 0.7, containing 5.27% Na, 7.14% S, and 15.87% Cl.

EXAMPLE II

Chlorinated sulfated tallow alcohols.—A tallow alcohol,

saponification No. 8.2, acid No. 1.5, I No. 54.1, percent hydroxyl 6.4, was chlorinated and sulfated as described in Example I, except that purification steps were omitted. Chlorine was run slowly into a solution of the tallow alcohol in 3 volumes of chloroform at -20° C . until an excess of chlorine was evident. Excess chlorine was expelled by a stream of nitrogen. The iodine absorption of the solution at this point was 0.13 g./100 ml. indicating almost complete reaction of chlorine was unsaturated constituents.

Without removal of solvent the chlorinated tallow alcohol was sulfated with 1.09 molar ratio of chlorosulfonic acid at 0° C . to 10° C . Methanol was added and the cold reaction mixture was neutralized with 18 N sodium hydroxide and evaporated to dryness to give a cream colored solid.

The solubility, surface active and detergent properties of this somewhat impure product were in general comparable to mixtures of pure compounds simulating sulfated tallow alcohol and sulfated chlorinated tallow alcohol. The solubility and foaming properties were better than those of a mixture of pure compounds simulating sulfated hydrogenated tallow.

EXAMPLE III

Detergent and surface active properties of sodium 9-10-dichlorooctadecyl sulfates.—The foaming and detergent properties of sodium 9,10-dichlorooctadecyl sulfates and mixtures containing them are shown in Table II.

Foam-height was measured by the Ross-Miles test, recorded as the height of foam five minutes after formation (Ross, J., and Miles, G. D., Oil and Soap 18, 99-102 (1941)).

Detergency was measured in an experimental washing machine (Terg-O-Tometer) with standard soiled cotton, initial reflectance relative to MgO as 100, 25.3, using 10 swatches per liter of solution, and washing for 20 minutes at 60° C . at 110 cycles per minute. Detergency was expressed as increase in reflectance, ΔR , after washing.

For comparison, values for sodium dodecyl sulfate, sodium oleyl sulfate, sulfated chlorinated tallow alcohol,

TABLE II
Foaming and detergent properties

5	10	Foam Height, mm., 60° C .		Detergency, 60° C . ΔR Values	
		0.25% in distilled water	0.1% in water of 100 p.p.m. hardness	0.1% in water of 100 p.p.m. hardness	0.25% in water of 300 p.p.m. hardness
Sodium dodecyl sulfate.....	175	248	24.8	24.5	
Sodium oleyl sulfate.....	240	226	34.8	24.0	
Sodium 9,10-dichlorooctadecyl sulfate (from oleyl alcohol).....	235	205	31.5	22.2	
Sodium 9,10-dichlorooctadecyl sulfate (from elaidyl alcohol).....	245	209	32.8	21.7	
Sulfated chlorinated tallow alcohol (of Example II, without purification).....	238	208	29.5	22.9	
Mixture A. Sulfated tallow alcohol.....	249	216	30.7	26.1

Mixture C. Sulfated chlorinated tallow alcohol.....	243	208	34.8	24.5	

25 In Table III the calcium stability, surface and interfacial tension, and wetting properties of the sodium 9,10-dichlorooctadecyl sulfates are compared with those for sodium dodecyl sulfate and sodium oleyl sulfate.

Calcium stability was measured by a modified Hart method (Wilkes, B. G., and Wickert, J. N., Ind. Eng. Chem. 29, 1234-9 (1937)).

30 Wetting properties are recorded as the sinking time for a standardized binding tape by the method of Shapiro (Shapiro, L., Am. Dyestuff Repr. 39, 38-45, 62 (1950)).

35 The sodium 9,10-dichlorooctadecyl sulfates have calcium stability values intermediate between those for sodium dodecyl sulfate and sodium oleyl sulfate. Surface and interfacial tension values are about the same as those for sodium oleyl sulfate. Wetting properties measured by sinking time show that the sodium 9,10-dichlorooctadecyl sulfates are quite stable to hydrolysis in boiling 1% sodium hydroxide, but like the other alcohol sulfates they are hydrolyzed in hot 5% sulfuric acid solution.

TABLE III
Surface active properties

Ca Stability, p.p.m. CaCO_3	Surface and Interfacial Tension, 0.1% Solns., dynes/cm. 25° C .	Sinking Time, 0.1% Concen. of Surface Active Agent, 25° C , Seconds					Boiled $\frac{1}{2}$ Hr. in 5% H_2SO_4	
		S.T.	I.T.	Distd. Water	1% NaOH	Boiled 4 Hrs. in 1% NaOH	5% H_2SO_4	
Na dodecyl sulfate.....	550	49.0	20.3	13	13	17	15	≥ 600
Na oleyl sulfate.....	>1,800	35.0	7.4	19	23	31	30	≥ 600
Na 9,10-dichlorooctadecyl sulfate (from oleyl alcohol).....	970	35.8	5.8	32	53	46	62	≥ 600
Na 9,10-dichlorooctadecyl sulfate (from elaidyl alcohol).....	950	35.8	6.0	39	66	57	70	≥ 600

and mixtures of pure compounds simulating the composition of sulfated tallow alcohol (A), sulfated hydrogenated tallow alcohol (B), and sulfated chlorinated tallow alcohol (C), are included. Mixtures A, B and C have the same composition as those similarly designated in Table I.

From Table II it is apparent that sodium oleyl sulfate and sodium 9,10-dichlorooctadecyl sulfates have similar solubility, foaming, detergent, and surface active properties. Sulfated chlorinated tallow alcohol has much better solubility than sulfated hydrogenated tallow alcohol, and better foaming properties in hard water.

We claim:

65 1. A detergent composition comprising an anionic detergent having a solubility in water at 25° C . of less than about .2% and having the general formula

70 wherein n is an integer selected from the group consisting of numerals 14 and 16 and M is an alkali metal, and as a solubilizing agent therefor, about from 10% to 50% of sodium 9,10-dichlorooctadecyl sulfate.

2. The detergent composition of claim 1 wherein the 75 anionic detergent is sodium hexadecyl sulfate.

3. The detergent composition of claim 1 wherein the anionic detergent is sodium octadecyl sulfate.
